CLAIM

The ornamental design for a point of sale device, as shown and described.

DESCRIPTION

FIG. 1 is an upper right front perspective view of a point of sale device; FIG. 2 is upper left rear perspective view of the point of sale device;

FIG. 3 is front plan view of the point of sale device;

FIG. 4 is a rear plan view of the point of sale device;

FIG. 5 is a left side plan view of the point of sale device;

FIG. 6 is a right side plan view of the point of sale device;

FIG. 7 is top plan view of the point of sale device; and,

FIG. 8 is bottom plan view of the point of sale device.

The broken lines in the drawings depict portions of the point of sale device that form no part of the claimed design.

1 Claim, 8 Drawing Sheets
